UNITED STATES PATENT OFFICE

2,351,771

CONVEYER

Charles I. Lattig, Columbus, Ohio, assignor to
The Jeffrey Manufacturing Company, a corpora-
tion of Ohio

Application May 4, 1942, Serial No. 441,610

11 Claims. (Cl. 198—52)

My invention relates to conveyers of the type in which endless chain flight conveyer mechanism is enclosed in a vertically rising casing and one of the objects of the invention is the provision of improved and efficient means for controlling feed of material to the conveyer to reduce to a minimum the congestion of the material in the casing.

Another object of the invention is the provision of mechanism for effecting such measured quantities of material between flights near the feed opening as to effect less quantities of such material in other portions of the conveyer distant from the feed opening.

A further object of the invention is the provision of means in the return run of a conveyer for tilting the flights of a chain flight conveyer to such angles as to have predetermined effective conveying areas and providing a different tilting of the flights in the working run of the conveyer.

Other objects of the invention will appear hereinafter, the novel features and combinations being set forth in the appended claims.

In the accompanying drawing,

Fig. 1 is a side elevational view of the complete conveyer embodying my improvements;

Fig. 2 is an enlarged sectional elevational view showing the conveyer mechanism associated with the feed opening;

Fig. 3 is a sectional elevation taken on the line 3—3 of Fig. 1 looking in the direction of the arrows;

Fig. 4 is a sectional elevation embodying a modification;

Fig. 5 is a sectional plan view taken on the line 5—5 of Fig. 2; and

Fig. 6 is a sectional elevation taken on the line 6—6 of Fig. 5 looking in the direction of the arrows.

By referring to Fig. 1 of the accompanying drawing, it will be seen that the complete conveyer comprises a totally enclosing casing or housing 7 comprising a vertical leg 8 and a horizontal leg 9. The casing or housing 7 is generally L-shaped and has within the same, separate tubes, the one designated 10 being the working tube and the other designated 11 being the return tube.

At the foot of the casing 7 there is an adjustable foot sprocket or wheel 12 and at the head thereof is a head shaft 13 carrying a head sprocket 14 which is provided with spaced sprocket teeth between which the links 15, 15' of an endless chain 16 travel. The chain 16 is

endless and extends between the drive sprocket 14 and the idler sprocket 12 in position to travel along the tubes 10 and 11 of the casing 7.

The head sprocket 14 is connected by sprocket chain gearing 17 to the electric driving motor 18. Granular material may be fed through the feed opening 19 into an upper tube section 27 of the horizontal leg 9 of the casing 7. The head section 20 of the casing 7 is provided with a discharge opening 21. In order to deliver material to the discharge opening 21 the chain 16 is driven upwardly along the tube 10 in the direction of the arrow 22.

Every other link 15' is provided with a projecting arm 23 to which is hinged or pivoted at 24 the leg 25 of a solid, notched flight 26. It will thus be seen that the flights 26 are spaced every other link of the chain 16, the links 15' being flight-carrying links and the links 15 being plain connecting links. In the upper tube section 27 of the horizontal leg 9 of the casing, the arms 23 of the links 15' project upwardly, while in the lower tube section 28 of the horizontal leg 9 the arms 23 project downwardly.

The tube sections 27 and 28 of the horizontal leg 9 are superimposed and the chain conveyer section in the return tube 11 may be said to be the return run, the working run being in the working tube 10. The chain conveyer in the upper tube section 27 moves to the left as viewed in Fig. 2 while in the lower tube section 28 the chain conveyer moves toward the right. In the lower tube section 28 the flights 26 are inverted relative to the flights in the upper tube section 27.

An important feature of my invention is the provision of mechanism in the upper tube section 27 to effect a smaller cross-sectional area for the passage of material than the cross-sectional area for the passage of material in the lower tube section 28. Measured quantities of material between flights adjacent the feed opening 19 may then be delivered to the lower tube section 28 with the assurance that sufficient space will be afforded in the working tube 10, particularly in the curved connecting portion of the same, for free transfer or flow of the material toward the discharge opening 21 without congestion or choking of the material in the casing 7.

At the bottom of the upper tube section 27 is a longitudinal chain guide formed by means of the parallel spaced-apart longitudinal strips 29, 29. On top of the strips 29, 29 are mounted the horizontal plates 30, 30 which may be se-

cured to the inner opposite walls of the tube section 27. Inasmuch as the plates 30, 30 may be secured to the strips 29, 29 as well as to the walls of the tube section 27 and project inwardly beyond the upper edges of the strips 29, 29, the chain 16 will be confined against movement relatively to the tube section 27 in all directions except longitudinally of the tube section 27. The inner edges of plates 30, 30 are spaced apart to form a longitudinal slot for receiving the projecting arms 23. The plates 30, 30 therefore in reality form a horizontal partition immediately above the chain, slotted longitudinally to permit free passage of the arms 23.

As shown in Figs. 2, 5 and 6, inclined ramps are provided to direct each flight from its position shown at the right-hand end of Fig. 2 to the plates 30, 30. In other words, as the flights move toward the feed opening 19, their lower edges 32, 32 will ride up the ramps 31, 31 onto the upper surfaces of the plates 30, 30 so that the upper edge 33 of each flight will be held closely adjacent to the roof of the tube section 27 as the flight approaches the feed opening 19 and as it recedes therefrom.

In order to close the notches in the flights as they approach the feed opening 19 and recede therefrom, I have secured to the edges of the plates 30, 30, the longitudinal members 34, 34 spaced apart at 35 for the passage of the legs 25 of the flights. The members 34, 34 may be curved at 36, 36 to converge to the slot 35 and thereby serve to guide the flight leg 25 into the slot 35. As the flights move toward the left as viewed in Fig. 2, the legs 25 and the members 34, 34 co-act to fill the notches and therefore the flight 26 spans the cross-sectional area available for the movement of material while between the flights near the feed opening. This effective cross-sectional area, however, is substantially less than the cross-sectional area of the lower tube 28.

When the flight 26 runs off the bottom of the upper tube section 27 it will be free to drop until the upper edge of the notch in the flight 26 strikes against the chain to effect a shaking off of adhering material. The material is delivered to the lower tube section 28 to the right of the sprocket 12 as viewed in Figs. 1 and 2. The material is thus delivered in measured quantities, because as each flight leaves the left-hand edge of the feed opening 19, the flight to the left thereof as viewed in Fig. 2, is still resting on the plates 30, 30 or on the tops of the members 34, 34 or on both the plates 30, 30 and the members 34, 34, the object being to close the flights across the effective cross-sectional area so that a measured quantity of material will be delivered to the lower tube section 28.

By varying the sizes of the flights and changing the co-acting flight-notch closing structure accordingly, the measured quantity of material to be delivered to the lower tube section 28 may be varied. In other words, by varying the projected area of the flight the effective cross-sectional area for the flow of material in the upper tube to the left of the feed opening 19 as viewed in Fig. 2, may be varied.

In any event, however, the cross-sectional area of the lower tube section 28 should be appreciably larger than the effective cross-sectional area in the upper tube. In the upper tube section 27 the flights are supported at an appreciable angle to the vertical. In the lower tube

section 28 the flights are inverted and occupy nearly vertical positions as permitted by the spacing of the edges 32, 32 at 37, 37 from the ceiling of the lower tube 28. In each case the flights substantially fill the cross-sectional area of the tube. Consequently more space or volume is provided between successive flights for movement of the material along the active or working run, particularly along the curved portion of the working tube 10 of casing 7, where on account of spillage of material from above and on account of spreading of certain portions of adjacent flights and movements of such portions back toward each other, the material tends to become congested.

When the chain travels toward the right in the lower tube section 28, as viewed in Fig. 2, the chain rests on the flights in the notches thereof but when the chain passes around the curved portion toward the vertical section of tube 10 the chain engages the inner wall of the tube in which it travels, while the lower edges of the flights remain in scraping contact with the wall adjacent the right-hand outer surface of the casing 7, as viewed in Fig. 1. It will thus be seen that in the tube 10 the flights act as scraper flights with ample space available for movement of the material relatively to the flights whenever there is any tendency to crowding or congestion. Furthermore, when the flights are traveling upwardly in the vertical leg of the working tube 10 of casing 7 they are nearly at right angles to the path of travel and they each exert a lifting force at spaced intervals to keep the material moving toward the discharge opening, as it is preferred to drive the endless chain conveyor continuously at a substantially constant speed. On account of the regulation of the feed to deliver measured quantities, the material can not be fed in too fast, and congestion during conveying operations to the discharge opening 21 is reduced to a minimum.

In Fig. 4 I have shown a modification in that strips 38, 38 of resilient material such as rubber, are secured to the under sides of the adjacent inner edges of the plates 30, 30 to extend toward each other and leave a narrow slot between the same. These resilient strips 38, 38 are adapted to engage the upwardly projecting legs 25 of the flights. This arrangement forms a seal to effect a reduction in amount of material that can enter into the chain guiding mechanism extending along the bottom of the tube section 27.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. In apparatus for conveying granular material, the combination with a casing having a feed opening, of conveying mechanism including solid type notched flights, fixed means in said casing adjacent to said feed opening for substantially closing the notches in said flights while approaching and adjacent said feed opening and while receding therefrom.

2. In apparatus for conveying granular material, the combination with a tubular passageway having a feed opening, of chain conveying mech-

anism having flights thereon movable along said passageway below said feed opening, and cam mechanism in said passageway in position to be engaged by said flights and constructed and arranged to move the latter above a horizontal plane extending through the top of the conveyer chain to effect confinement of a predetermined volume of material between adjacent flights.

3. In apparatus for conveying granular material, the combination with a conduit, of a chain conveyer having flights thereon, guiding mechanism for the chain of the conveyer, a slotted transverse partition in said conduit in a horizontal plane above said guiding mechanism, and means for guiding said flights onto said transverse partition to slide along the latter.

4. In apparatus for conveying granular material, the combination with a support, of a chain flight conveyer including notched flights pivoted at intervals to upwardly extending arms on spaced links of the chain, a transverse slotted partition, said arms being movable along the slot in the partition, guide mechanism below the slot for said chain, and means supported on the partition to fill the slots in the flights as the latter move along said support.

5. In apparatus for conveying granular material, the combination with a conduit, of a chain flight conveyer including notched flights pivotally connected to spaced apart links of the chain, guiding mechanism for the chain, means for supporting the trailing edges of the flights to hold the upper edges of the flights in close proximity to the roof of said conduit, and mechanism on said supporting means adapted to fill the notches in the flights as the latter are moved through said conduit.

6. In apparatus for conveying granular material, the combination with a support, of a chain flight conveyer movable along said support and including flights connected to arms projecting upwardly from spaced links of the chain, guiding mechanism for said chain, means supporting the bottom edges of said flights above said chain, and resilient strips on said supporting means in position to engage the said upwardly projecting arms.

7. In apparatus for conveying granular material, the combination with a support, of a chain flight conveyer movable along said support and including flights connected to arms projecting upwardly from spaced links of the chain, guiding means for the chain, spaced members forming a transverse partition in position to be engaged by said flights, and resilient strips on the

inner edges of said members to form a seal to reduce to a minimum the material entering said chain guiding means.

8. In apparatus for conveying granular material, the combination with a horizontal working tube having a feed opening, of a return tube, a chain flight conveyer movable along said tubes comprising notched flights pivoted to the chain, guiding mechanism for the chain in the return tube, guiding means for the flights in the return tube to hold the flights in positions to span the effective cross-sectional area in the return tube, and stationary means for spanning the notches in the flights as they approach the feed opening and recede therefrom, the construction and arrangement being such that the cross-sectional area of the working tube is larger than the effective cross-sectional area of the return tube.

9. In a conveyer, the combination with a casing forming a working tube leading to an outlet, of conveyer means for conveying material through said tube to said outlet including pivoted flights, means for feeding material to a straight portion of said casing in limited quantities including means for tilting said pivoted flights so that the available volume between successive flights is less than between said successive flights while thereafter traveling through said working tube.

10. In a conveyer, the combination with a casing forming a working tube section and a communicating feed tube section, the feed tube section having a smaller cross-sectional area than the working tube section, conveyer means including pivoted flights traveling through said sections to convey material successively through them, said flights being constructed substantially to fill the cross-sectional area in each of said sections, and means for tilting said flights while traveling through said feed tube section so they sweep a smaller area than when traveling through said working tube section.

11. In a conveyer, the combination with a casing forming a working tube section and a communicating feed tube section, the feed tube section having a smaller cross-sectional area than the working tube section, conveyer means including pivoted flights traveling through said sections to convey material successively through them, said working tube having a curved and upwardly extending portion, and means for tilting said flights while traveling through said feed tube section so they sweep a smaller area than when traveling through said working tube section.

CHARLES I. LATTIG.
